SAFETY RAZOR

William Harman Black, New York, N. Y.

Application October 26, 1937, Serial No. 171,919

12 Claims. (CL 30—60)

This invention relates to safety razors, and more particularly to that type of safety razor in which a blade is clamped and fixed between a guard and cap.

5 The primary object of the invention is to provide this type of razor which can be manually operated so as to turn the razor blade over, that is to say, give a rotary or turning movement of approximately 180 degrees to the blade so that it 10 is reversed in the razor without removing the blade from the razor.

I have discovered that a blade rests if its position is changed from side to side every time after a shave, and the razor of this particular 15 application accomplishes this movement by mechanical means which permits the operation without the necessity of touching the blade or its cap with the fingers of the hand.

The invention embodies many novel features 20 of construction and combinations and arrangements of parts, all of which will be more fully hereinafter described and pointed out in the claims.

In the accompanying drawing—

25 Fig. 1 is a top plan view of the razor with its parts in closed position;

Fig. 2 is a view in longitudinal section on the line 2—2 of Fig. 1;

Fig. 3 is a view in transverse section on the 30 line 3—3 of Fig. 2;

Fig. 4 is an end view looking at the right-hand end of Figs. 1 and 2;

Fig. 5 is a view similar to Fig. 3 but showing the razor in open position;

35 Fig. 6 is a fragmentary sectional detail view on the line 6—6 of Fig. 2, but showing the position of the parts when the razor is open, that is to say, as shown in Fig. 5 of the drawing;

Fig. 7 is a view in elevation looking at the side 40 of the razor with the latter in closed position;

Fig. 8 is a top plan view of the razor with the same in open position;

Fig. 9 is a detail view mainly in elevation but partly in section, of my improved elevator.

45 My improved razor includes a guard indicated generally by the reference character A with which a cap B cooperates to clamp and flex a blade C.

The guard A constitutes an inverted channel-shaped member with parallel upwardly projecting webs 10 at its side edges which have outwardly flared flanges 11 at their upper extremities and toothed extensions 12 on the flanges, all of which constitute a guard against which the 55 blade C is clamped by the cap B.

The guard A is fixedly secured to a tubular handle D, said handle projecting downwardly from the center of the base of the channel-shaped guard A.

The reference character E is employed to indicate generally an elevator which is in the form of a frame having a base member 14 with upwardly projecting arms 15 at its ends, and this base member 14 and arms 15 fit neatly within the guard A and are movable vertically therein. 10

The elevator E is provided with a downwardly projecting screw-threaded rod 16 fixedly secured to the center of the base 14 and projecting into the tubular handle D where it meshes with internal screw threads 17 in a sleeve 18 which has 15 rotary mounting in the handle. This sleeve is manually turned preferably by means of a milled head 19 on the lower end of the same and which is located outside of the handle D, and a screw or other form of pin 20 is projected through the 20 milled head 19 into an annular groove 21 in the handle D so as to prevent longitudinal movement of the sleeve but permit free rotary movement thereof.

To limit the upward movement of the screw-threaded rod 16 in the sleeve 18 a headed screw 22 may be capped into the lower end of the rod 16 and engage the threaded portion 17 of the sleeve 18 when the elevator E reaches the extreme of its upward movement. 30

The cap B at its ends is provided with downwardly projecting arms 23 which at their lower portions are pivotally connected to the arms 15 of elevator E by means of pivot pins 24, and it will be noted that these pivot pins 24 are at one 35 side of the longitudinal centers of the arms 23.

One arm 23 at its lower extremity adjacent the pivot 24 is provided with a laterally projecting finger 25 which, when the elevator moves upward to the desired elevation, engages a fixed lug 26 on the end of the guard A so that a continued upward movement of the elevator will cause the cap E to swing laterally from the position shown in Figs. 3 and 4 to the position 45 shown in Fig. 5.

The upwardly projecting arms 15 of the elevator E are provided adjacent their upper ends with slots 27 which receive trunnions 28 on the ends of my improved blade holder 29. This blade 50 holder is in the form of a bar having longitudinal ribs 30 thereon to enter slots or openings 31 in the blade C, and between these ribs 30, I provide a turn-button 32 which may be located in alignment with the ribs to receive the blade thereon 55

and then turn at right angles so as to clamp the blade on the blade holder.

Of course the invention is not limited to any specific means for clamping the blade on the blade holder, and I have illustrated in Fig. 9 of the drawing a modified form which dispenses with the turnbutton 22 and provides a slotted or notched tongue 33 at one end of the blade holder under which the blade is positioned and then snapped or sprung into position over the ribs 36.

A ratchet pinion 34 is fixedly secured to the blade holder at one end thereof and is engaged by a ratchet rack 35. This ratchet rack 35 is in the form of a lever pivotally mounted near its lower end on a pin 24 connected to an elevator arm 18. This ratchet rack at its lower end below its pivot is formed with an outwardly projecting preferably curved finger 36 which rides in a slot 37 in one of the side webs 18 of the guard A which causes the ratchet rack 35 to pivot in both directions by reason of its contact with the ends of the slot 37.

The operation of the razor is as follows: The razor is held in a vertical position with the fingers 23 of one hand grasping the handle B, and the thumb and finger of the other hand grasping the head 19 to turn the same. Assuming the razor to be in closed position, as indicated in Figs. 1, 2, 3, 4, and 7 of the drawing, the operator turns the head 19 in a direction to cause the elevator E to move upward by reason of the screw-threaded engagement between the rod 18 and the sleeve 16.

When the elevator moves upward a necessary distance, the finger 26 of the arm 23 of cap B 35 will engage the lug 26 on the guard A, and as the upward movement of the elevator continues this engagement of the finger with the lug will cause the cap to swing on the pivot 24 from its closed position to its open position as indicated by Fig. 5 of the drawing. A portion of this movement of the cap, that is, the extreme of this opening movement, is due to gravity.

When the cap is moved to its open position and the upward movement of the elevator is continued, the finger 36 on the ratchet rack 35 will engage the upper end of the slot 37 and cause the ratchet rack to pivot in a direction to turn the ratchet pinion 34 and the blade holder 29 a distance of 180 degrees, thus turning the blade holder with the blade therein and reversing the position of the blade in the razor. As this operation is completed the upward movement of the elevator is stopped or terminated as, for example, by means of the screw 22 in the end of the rod 18.

When this operation of opening the razor is completed, the operator turns the head 19 and sleeve 16 in a direction opposite to that which he has just previously turned the same to open the razor which causes the rod 18 and the elevator E to move downwardly in the guard A. As the elevator moves downwardly, the edge of the arm 23 of cap B is engaged by the lug 26 which exerts a cam action on the arm 23 which causes the cap to swing from its open to its closed position and securely clamp the blade C between the cap and the guard.

As the elevator nears the extremity of its downward movement the finger 36 of the ratchet rack 35 will engage the lower end of the slot 37 in the guard A and will cause said ratchet rack to swing in a direction opposite to that formerly described, and it will be noted that by reason of the fact that the trunnions 28 of the blade holder 29 are in slots 37 of the elevator, the blade holder is

permitted a certain amount of upward movement in the elevator. Thus the ratchet rack can move in one direction, which is the movement last described, without imparting any turning movement to the blade holder and thus reset itself for another operation.

While I have illustrated and described what I believe to be a preferred embodiment of my invention, it is obvious that various changes might be made in the general form and arrangement of parts without departing from the invention, hence I do not limit myself to the specific details set forth but consider myself at liberty to make such changes and alterations as fairly fall within the spirit and scope of the appended claims.

I claim:

1. A safety razor including a guard, a blade holder and a cap adapted to clamp the blade in the holder between the cap and the guard, means for elevating the blade holder and cap, means for moving the cap from its position above the blade holder, and means for turning the blade holder when the latter is in an elevated position above and parallel with the guard.

2. A safety razor including a guard, a blade holder and a cap adapted to clamp the blade in the holder between the cap and the guard, means for elevating the blade holder and cap, means for moving the cap from its position above the blade holder, and means for turning the blade holder when the latter is in an elevated position above and parallel with the guard, said last mentioned means comprising an elevator to which the cap and the blade holder are connected, and inter-engaging means between the cap, blade holder, and guard.

3. A safety razor including a guard, a blade holder and a cap adapted to clamp the blade in the holder between the cap and the guard, means for elevating the blade holder and cap, means for moving the cap from its position above the blade holder, and means for turning the blade holder when the latter is in an elevated position above and parallel with the guard, said last mentioned means comprising an elevator to which the cap and the blade holder are connected, and inter-engaging means between the cap, blade holder, and guard, a threaded rod affixed to the elevator and movable in the handle, and a sleeve mounted to turn in the handle and having threaded engagement with the rod.

4. A safety razor including a guard, a handle secured to the guard, an elevator movable in the guard, a cap pivotally connected to the elevator, a blade holder having rotary mounting in the elevator, cooperating means between the guard and cap causing the cap to swing from closed to open position when the elevator is moved in one direction and from open to closed position when the elevator is moved in the opposite direction, and means for turning the blade holder and blade therein through an arc of approximately 180 degrees as the elevator reaches the extreme of its movement in a direction to open the razor.

5. A safety razor including a guard, a handle secured to the guard, an elevator movable in the guard, a cap pivotally connected to the elevator, a blade holder having rotary mounting in the elevator, cooperating means between the guard and cap causing the cap to swing from closed to open position when the elevator is moved in one direction and from open to closed position when the elevator is moved in the opposite direction, and means for turning the blade holder and blade therein through an arc of approximately 180 degrees.

5 degrees as the elevator reaches the extreme of its movement in a direction to open the razor, said last mentioned means including a ratchet pinion on the blade holder, a pivoted ratchet rack on the elevator engaging the pinion, and means operatively connecting the rack and the guard.

6. A safety razor including a guard, a handle secured to the guard, an elevator movable in the guard, a cap pivotally connected to the elevator;

10 a blade holder having rotary mounting in the elevator, cooperating means between the guard and cap causing the cap to swing from closed to open position when the elevator is moved in one direction and from open to closed position when the

15 elevator is moved in the opposite direction, and means for turning the blade holder and blade therein through an arc of approximately 180 degrees as the elevator reaches the extreme of its movement in a direction to open the razor, said

20 last mentioned means including a ratchet pinion on the blade holder, a pivoted ratchet rack on the elevator engaging the pinion, a finger on the ratchet rack movable in a slot in the guard and causing the rack to swing in opposite directions

25 when the finger engages the opposite ends of the rack.

7. A safety razor including a guard, a handle secured to the guard, an elevator movable in the guard, a cap pivotally connected to the elevator,

30 a blade holder having rotary mounting in the elevator, cooperating means between the guard and cap causing the cap to swing from closed to open position when the elevator is moved in one direction and from open to closed position when

35 the elevator is moved in the opposite direction, and means for turning the blade holder and blade therein through an arc of approximately 180 degrees as the elevator reaches the extreme of its movement in a direction to open the razor, said

40 last mentioned means including a ratchet pinion on the blade holder, a pivoted ratchet rack on the elevator engaging the pinion, a finger on the ratchet rack movable in a slot in the guard and causing the rack to swing in opposite directions

45 when the finger engages the opposite ends of the rack, said blade holder having a limited vertical movement in the elevator.

8. A safety razor including a guard, a handle secured to the guard, an elevator movable in the guard, a cap pivotally connected to the elevator,

50 a blade holder having rotary mounting in the elevator, cooperating means between the guard and cap causing the cap to swing from closed to open position when the elevator is moved in one direction and from open to closed position when the elevator is moved in the opposite direction, and means for turning the blade holder and blade therein through an arc of approximately 180 degrees as the elevator reaches the extreme of its

55 movement in a direction to open the razor, said last mentioned means including a ratchet pinion

on the blade holder, a pivoted ratchet rack on the elevator engaging the pinion, a finger on the ratchet rack movable in a slot in the guard and causing the rack to swing in opposite directions when the finger engages the opposite ends of the rack, longitudinal ribs on the blade holder adapted to enter a slot in the blade, and a turnbutton on the blade holder adapted to clamp the blade to the holder.

9. A safety razor including a guard of general 10 inverted channel shape, an elevator movable in the guard, a cap pivotally connected to the elevator, a blade holder having rotary mounting in the elevator, means for moving the elevator in the guard, means for causing the cap to swing 15 out of position above the guard when the blade holder is elevated, and means adapted to turn the blade holder when the elevator approaches the extreme of its upward movement.

10. A safety razor including a guard, a handle 20 affixed to the guard, an elevator movable in the guard, a cap pivotally connected to the elevator, a lug on the guard, a finger on the cap adapted to engage the lug and cause the cap to swing from a position above the guard to a position 25 outside of the guard and vice versa, a blade holder having rotary mounting in the elevator, and means for turning the blade holder when the elevator nears its highest position.

11. A safety razor including a guard, a handle 30 affixed to the guard, an elevator movable in the guard, a cap pivotally connected to the elevator, a lug on the guard, a finger on the cap adapted to engage the lug and cause the cap to swing from a position above the guard to a position 35 outside of the guard and vice versa, a blade holder having rotary mounting in the elevator, and means for turning the blade holder when the elevator nears its highest position, a threaded rod affixed to the elevator and projecting into the handle, a sleeve mounted to turn in the handle and having threaded engagement with the rod, and a knob on the lower end of the sleeve outside of the handle.

12. A safety razor including a guard, a handle 40 affixed to the guard, an elevator movable in the guard, a cap pivotally connected to the elevator, a lug on the guard, a finger on the cap adapted to engage the lug and cause the cap to swing from a position above the guard to a position 45 outside of the guard and vice versa, a blade holder having rotary mounting in the elevator, and means for turning the blade holder when the elevator nears its highest position, a threaded rod affixed to the elevator and projecting into the handle, a sleeve mounted to turn in the handle and having threaded engagement with the rod, a knob on the lower end of the sleeve 50 outside of the handle, and means for limiting the movement of the elevator.

WILLIAM HARMAN BLACK.
